CLAIM

The ornamental design for a Dutch oven side handle, as shown and described.

DESCRIPTION

FIG. 1 is a perspective view of the “Dutch oven side handle” showing my new design;

FIG. 2 is a top plan view thereof;

FIG. 3 is a front elevation view thereof;

FIG. 4 is a right side elevation view thereof; the left side elevation view being the mirror image thereof;

FIG. 5 is a bottom plan view thereof; and,

FIG. 6 is a back elevation view thereof.
